Primary Examiner — Karen E Eldridge Powers

(57) **CLAIM**

The ornamental design for a skin care device, as shown and described.

DESCRIPTION

FIG. 1 is a first perspective view of an embodiment of a skin care device;

FIG. 2 is a second perspective view of the embodiment thereof;

FIG. 3 is a front elevation view of the embodiment thereof; FIG. 4 is a rear elevation view of the embodiment thereof; FIG. 5 is a left side elevation view of the embodiment thereof;

FIG. 6 is a right side elevation view of the embodiment thereof;

FIG. 7 is a top plan view of the embodiment thereof; and, FIG. 8 is a bottom plan view of the embodiment thereof. The broken lines shown in the drawings are included for the purpose of illustrating portions of the article that form no part of the claimed design.

1 Claim, 8 Drawing Sheets
